UNITED STATES PATENT OFFICE.

SAMUEL C. HORTON, OF ST. PAUL, MINNESOTA.

BOX.

1,105,788.

Specification of Letters Patent.

Patented Aug. 4, 1914.

Application filed August 20, 1910. Serial No. 578,219.

To all whom it may concern:

Be it known that I, SAMUEL C. HORTON, a citizen of the United States, residing at St. Paul, in the county of Ramsey and State of Minnesota, have invented a new and useful Improvement in Boxes, of which the following is a specification.

My invention relates to improvements in boxes and its principal object is to secure a bottle holding box which will be convenient for packing and shipping, easy to handle, readily sealed against opening and provided with a cover which can not be removed from the box and will yet be convenient in form. This box is fitted with hand holes for lifting and carrying, and, as it is desirable to keep certain liquors in the dark, sliding covers are provided for the hand holes which may be closed when the boxes are in storage. One of the principal advantages of my box is the foldable cover which on being opened, drops down beside the box and out of the way.

I have illustrated one form of my device in the accompanying drawings which form part of my specification and of which—

Figure 1 is a perspective of my improved box; Fig. 2 is a transverse section through the center of the box; Fig. 3 is an enlarged section showing the lock; Fig. 4 is a front view of the seal, and Fig. 5 is a section showing the hand hole and its cover.

In the above drawing A is a box of the ordinary size for holding a dozen bottles and having ends 2 and sides 3 and 4. Each of the ends 2 of the box is formed with a groove 5 on its inner side adapted to receive a longitudinal sliding cover B to close the box. Near the top of each end on the center line 40 of the box is an ordinary slot or hand hole 6 by means of which the box can be picked up and carried. On the inside of each end 2 immediately above and below the hand hole 6 are pressed metal strips 7 forming grooves 45 in which a strip of metal 8 may be slid over the hand hole. This sliding cover 8 is formed with an indent 9 near one end, presenting a recess toward the outside of the box by means of which the cover may be slid 50 off from over the hand hole allowing a man carrying the box to secure a hold upon the edge of the hand hole. The metal strips 7 may be formed integral with the ends or secured to the box in any suitable manner as 55 by the screws 10. Within the box is a rack 11 for holding bottles. A cover formed of

two pieces 12 and 13 fastened together by hinges 14, is fitted to the grooves 5 in the ends 2 of the box A. The part 12 of the cover, which lies nearest the front side 3 of the box is relatively narrow and is adapted 60 to remain upon the box and prevent the removal of the entire cover from it. This is secured by a stop 15 attached to the under-side of the cover 12 by screws 16 or other 65 suitable means and is fitted to prevent the cover from being removed from the grooves 5, by coming in contact with the side 4 of the box. The narrow portion 12 of the cover is reinforced upon its upper side by a strip 70 17 which prevents the breaking down of the edge of the cover and raises it to a level with the top line 18 of the ends and front side of the box. The folding portion 13 of the cover is also fitted with a reinforcing strip 19 75 which is placed at its back edge thus giving a paneled effect to the top of the box when closed.

On the under side of the cover 12 at the center of its length is a spring metal catch 80 20 formed with a shoulder 21 and attached to the cover 12 by screws 22 or in any suitable manner. The shoulder 21 is fitted to snap over a shoulder 23 in an aperture 24 in the front wall 3 of the box when the cover B is 85 in its closed position. The shoulder 23 is formed with a metal plate 25 or in any suitable manner and is provided with a metal tongue 26 against which the shoulder 21 drops when in its closed position. In the 90 tongue 26 and the shoulder 21 are corresponding openings 27 and 28 through which a sealing wire 29 may be passed and fastened with a seal 30 as illustrated. The aperture 24 is closed on the outside by a hinged metal 95 cover 31 pivoted on a screw 32 and having a hook 33 fitted to engage a pin 34 to hold the cover in its closed position.

The box may be closed and sealed by sliding the cover B shut, causing the spring 100 catch 20 to engage the shoulder 23, and passing a seal through the openings 27 and 28 and closing the cover 31. To open the box the seal is broken, the spring catch 20 raised, and the cover slid back until the stop 15 105 strikes the wall 4 of the box. The part 18 of the cover then extending backward, swings down upon the hinges 14 beside the box making it convenient to pack in its open position. The hand hole covers 8 may be used to protect the contents of the box from light whenever desirable.

While the drawings illustrate a frame structure, I contemplate constructing my invention from metal or other suitable material.

- 5 In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claim.
- 10
- 15 Having described my invention, what I claim as new and desire to protect by Letters Patent is:—

A box, comprising, inclosing side and end walls and bottom, two opposite walls thereof having parallel grooves near their upper

edges, a cover sliding in said grooves and lying in one plane to close said box, said cover being formed in two parts hinged to fold on each other when one of said parts is withdrawn from said grooves and one of said parts having a stop to prevent the removal of the same from the grooves in said walls whereby said cover may have one part folded down on the outside of said box and the other part retained in said grooves to maintain said cover in connection with said box when the same is open.

In testimony whereof, I have signed my name to this specification, in the presence of two subscribing witnesses.

SAMUEL C. HORTON.
